ABSTRACT OF THE DISCLOSURE

Film forming synthetic resinous polymers having the repeating unit

have been found to be effective binders for beaded inorganic salt base products such as synthetic detergents.

This invention relates to water soluble or water dispersible spray-dried products having improved mechanical stability. More particularly, the invention is directed to inorganic salt base products in the form of spray-dried beads possessing improved resistance to attrition resulting from their being handled by various mechanical devices such as belt conveyors, bucket elevators, discharge into and passage through hoppers and bins, and due to vibration during shipment via railroads and motor trucks.

The invention aims to improve any of a variety of spray dried compositions usable alone or admixed with other materials, depending upon the nature and intended purpose of the final product. Primarily the invention is concerned with what may be termed salt-base-containing compositions usable in a variety of household and industrial products, and which include one or more inorganic water soluble salts, of which so-called builder salts such as the alkali metal phosphates (e.g. trisodium, tetrasodium phosphates and sodium tripolyphosphate), sulfates, carbonates and silicates, are illustrative. For various reasons it is advantageous to produce such salt bases in the form of spray dried particles in hollow bead form, and in which the alkaline salt or salt mixture is the major constituent of the beads. Thus, the beads may range in composition from virtually 100% salts, to compositions that may contain relatively small quantities of other materials such as surfactants, dyes, oils and perfumes, depending upon the end product desired.

In terms of end product, the invention contemplates improved bleaching and disinfecting products in which a spray dried base is mixed with solid organic chlorinated material whose available chlorine content is such as to render the product effectively usable for household and industrial bleaches. Accordingly, in the broader contemplations of this aspect of the invention, we may use any of various known types of solid chlorinated organic materials having desirable content of available chlorine.

With respect to dry bleach compositions, the spray dried base may contain a relatively small amount of a suitable surfactant, preferably anionic, to give the product detergents and foaming properties. It is to be understood that we may use any of the many known soaps or synthetic surfactants as the detergents component of the base, and that the prior art and commercial practice pertaining to household and commercial detergents is replete with known surfactants that are used in solid or spray dried detergents. In a spray dried base to be formulated with a solid organic chlorinated

2

material, we prefer to use a suitable anionic surfactant such as the "Oronite" type of alky aryl sulfonates, e.g. alkyl metal dodecyl benzene sulfonate, although at greater expense, other surfactants such as the fatty acid sulfates, e.g. alkali metal lauryl sulfate, may be used.

Various advantages of the invention are applicable to detergent compositions totally containable in the spray dried beads, particularly with respect to lower active level detergents where the surfactant content may not exceed about 20% by weight of the bead composition. The relatively high preponderance of the builder salt content, e.g. in excess of 75% and commonly greater than 80%, normally would render the beads subject to undesirably high attrition losses which are desirably minimized in accordance with the invention. Thus where the spray-dried material is a total detergent formulation, the beads will contain not more than about 20% non-ionic, cationic or anionic organic surfactant, the balance consisting of alkaline builder salt together with minor percentages of such additives as dyes, brighteners, oils and the like, all in uniform admixture resulting from the spray drying of an aqueous solution or slurry of the components.

The mechanical aspects of conventional spray drying are well known. Generally the procedure involves forming an aqueous slurry of product components, spray drying the slurry to solid hollow bead form, and collecting and transferring the beads to a packaging station by systems that may vary in detail but which conventionally will involve the use of traveling conveyors, elevators and possibly mixers, all of which subject the beads to vibration or agitation, and therefore tend to cause attrition losses in advance of packaging. Thereafter these packaged products are subject to further attrition losses as a result of vibration in transportation to the point of consumption.

Resistance to bead break-down by attrition is of considerable economic importance because attrition produces a change in the bulk density of the product, a property of substantial concern in packaging. The bulk density determines the weight of material charged to the package by a packaging machine of the constant volume type, or the volume charged by a machine of the constant weight type. Hence, uncontrolled changes in bulk density lead to over or under fill of the packages, either of which conditions results in economic loss to the manufacturer because of such factors as package rejection by quality control, customer dissatisfaction, excessive weight fill, overflow of packages on packaging machine, etc.

It is customary to control the bulk-density of the product by adjusting one or more of the several variables associated with the operation of the spray-dried or film drier. However, if the dried product possesses poor mechanical strength, varying and unpredictable amounts of attrition occur between the dryer and the point of packaging. It has now been found that by adding stable, film forming polymeric materials to the detergent composition to be spray dried, the mechanical strength of the spray-dried beads can be strengthened sufficiently to avoid the attrition necessarily attendant upon the various handling processes subsequent to the drying operations.

In reference to chlorinated solid bleach compositions contemplated by the invention, we may typically, though preferably, select the chlorinated component from the heterocyclic N-chloro imides, which are cyclic imides having from 4 to about 6 members in a ring having the following structure:

Usable compounds include the N-chloro derivatives of

cyanuric acid (i.e. mono-, di-, and trichlorocyanuric acid) and hydantoin as well as N-chloro succinimide, N-chloro malonimide, N-chloro phthalimide and N-chloro naphthalimide. Most effective are those imides containing a plurality of chlorine-carrying nitrogen atoms, e.g. trichlorocyanuric acid, dichlorocyanuric acid, alkali metal salts of dichlorocyanuric acid, and the N-chloro hydantoins. Suitable N-chloro hydantoins include 1,3-dichloro - 5,5 - dimethyl hydantoin, N-monochloro-C, C-dimethylhydantoin, methylene-bis-(N-chloro-C, C-dimethylhydantoin); 1,3-dichloro-5-methyl-5-isobutylhydantoin; 1,3-dichloro-5-methyl-5-ethylhydantoin; 1,3-dichloro-5,5-diisobutylhydantoin; 1,3-dichloro-5-methyl - 5 - n-amylydantoin, and the like. Among all such compounds, we prefer the alkali metal salts of dichlorocyanuric acid.

As previously indicated, the spray dried base for most products will contain a suitable organic detergent, the content of which may range from as low as about 1% to as high as about 20% in formulations where the spray dried material constitutes the complete product. With respect to solid bleach compositions, the spray dried base normally will contain between about 1 to 5% of surfactant, the beads being uniformly admixed with a selected chlorinated material which may constitute between about 20 to 25 weight percent of the mixture. Using the preferred sodium or potassium salts of dichlorocyanuric acid as the chlorinated material, the latter desirably will constitute between about 5-9% of the total mixture of the chlorinated salt and spray dried base in household bleaches, and between about 15-20% in industrial bleaches.

Suitable anionic detergents are the soaps and the sulfated and sulfonated synthetic detergents, especially those anionic detergents having about 8 to about 26 and preferably about 12 to about 22 carbon atoms to the molecule. The sulfated and sulfonated compounds are well known in the art and may be prepared from suitable organic materials capable of sulfonation or sulfation. Preferred are the aliphatic sulfates and sulfonates of about 8 to 22 carbon atoms, an the alkyl aromatic sulfonates. The latter may be mononuclear or polynuclear in structure. More particularly, the aromatic nucleus may be derived from benzene, toluene, xylene, phenol, cresols, phenol ethers, naphthalene, derivatives of phenanthrene nuclei, etc. The alkyl group may vary similarly. Thus, the alkyl group may be straight or branch chained and may consist of such radicals as dodecyl, pentadecyl, octyl, nonyl, decyl, keryl, mixed alkyls derived from fatty materials, cracked paraffin wax olefins, and polymers of lower mono olefins, etc.

Examples of suitable alkyl aromatic sulfonate detergents are the propylated naphtholene sulfonates, the mixed butyl naphthalene sulfonates, tetrahydronaphthalene sulfonates, the various butylated diphenyl sulfonates and phenyl-phenol sulfonates. Preferred are the higher alkyl aromatic sulfonates the sulfonated and alkylated benzene type compounds wherein the alkyl group is at least 8 and preferably about 10 to about 16 carbon atoms.

Other suitable surfactants are the surface-active sulfated or sulfonated aliphatic compounds, preferably having 8-22 carbon atoms, such as the sulfuric acid esters of polyhydric alcohols incompletely esterified with higher fatty acids, e.g. coconut oil monoglyceride monosulfate, tallow diglyceride monosulfate; the long chain pure or mixed alkyl sulfates, e.g. lauryl sulfate, cetyl sulfate; the hydroxy sulfonated higher fatty acid esters, e.g. higher fatty acid esters of low molecular weight alkylol sulfonic acids, e.g. fatty acid esters of isethionic acid; the fatty acid ethanolamide sulfates; the fatty acid amides of amino alkyl sulfonic acids, e.g. lauric amide of taurine, and the like.

The cationic detergents include the long chain alkyl quaternary ammonium compounds, e.g. cetyl quaternary ammonium salts, which include those salts wherein the nitrogen atom may be part of an open chain or hetero-

cyclic structure such as cetyl tri - methyl ammonium chloride and cetyl pyridinium chloride. Other cationic agents are the diethylene amino ethyl oleyl amides.

Non-ionic surfactants include the polyoxyethylene ethers of alkyl aromatic hydroxy materials (e.g. the alkylated polyoxyethylene phenols) the polyoxyethylene ethers of long chain aliphatic alcohols, and the polyoxyethylene ethers of hydrophobic propylene oxide polymers.

Particularly effective for incorporation in high builder salt compositions to produce dried particles of increased mechanical strength are copolymers having in the particles the following formula:

In this formula n is the degree of polymerization to high molecular weight in excess of 10,000, A is hydrogen and B is the same as the unit shown within the brackets except that it has an ethylene linkage in place of two of the hydrogen atoms. Thus, B may be

The exact position of this ethylene linkage is indeterminate by presently known methods. The principal significance of molecular weight is that the polymeric group be sufficiently great in number that the material is capable of drying from solution or dispersion in the salt solution, in thin film form.

Commercially this copolymer in the anhydride form has been available as early as September 1961, as solid water soluble ethylene maleic anhydride resin sold by Monsanto Chemical Co., under the name, "EMH Resin DX840-81." This product is described by Monsanto as having a viscosity of 80,000 centipoises (measured at 25° C. in a 1% solution at pH 9 using a Brookfield Viscometer, No. 6 spindle at 5 r.p.m.). This is representative of a molecular weight in excess of 10,000.

While the possibility of incorporating the resinous additive in a relatively broad range of about 0.1% and 5% of the bead composition is contemplated, in practice and because of the efficacy of this resin, it has been found that around 0.4% of the resin will satisfactorily reinforce the beads.

When this resin was added in the amount specified below in Table I, to a standard aqueous slurry of 60% solids content (solids composition by weight: 4.25% sodium dodecylbenzenesulfonate, 16.5% tetrasodium pyrophosphate, polymeric resin (X), and salt cake q.s. to 100%), and a film was prepared and dried in a standard reproducible manner, the following relative strength values were obtained for films containing and lacking the resin.

TABLE I.—RELATIVE FILM STRENGTHS

60	Resin Added	Percent Added	Relative Film Strength
	None	0.0	1.00
	EMA Resin DX840-81	0.4	2.28

65 It has been shown that there is good correlation between the film strength as determined by the forementioned procedure and the strength of the shell-like structure of the beads produced in conventional plant-sized spray-drying equipment as determined by the behavior in plant 50 mechanical handling and packaging equipment.

The following are cited as illustrative examples of spray dried materials formulated in accordance with the invention. Each of these compositions is predominately builder salt with relatively low surfactant content in Example 1, and higher amount of surfactant in Exam-

ple II, which represent products usable as household detergents:

EXAMPLE I

Formulas with the following composition have been mixed and spray dried in plant production:

	Formula A, Percent	Formula B, Percent
Sodium dodecyl benzene Sulfonate	4.25	4.00
Tetrasodium Pyrophosphate	16.50	16.50
Ethylene Maleic Anhydride (Copolymer EMA Resin DX 50-81)	0.375	0.40
Dyes, Deodorant Oil, Mineral Oil	78.875	78.725
Sodium Sulfate	100.00	100.00

As can be noted, the only differences between Formulas A and B are the slight changes in the sodium alkyl aryl sulfonate and sodium sulfate levels and the addition of 0.4% ethylene maleic anhydride copolymer in Formula B. However, the dried product of Formula B consistently had much greater bead stability than the dried product of Formula A. In a specific instance, the bulk density of the product out of the bottom of the spray drier was able to be raised from 240 to 300 grams/liter in order to meet a packaging specification of 326 grams/liter. Additionally, the product of Formula B has more uniformity in particle size and is improved in the resulting appearance.

EXAMPLE II

Detergents with the following compositions were mixed and spray dried in plant production.

	Formula C, Percent	Formula D, Percent
Sodium dodecyl benzene sulfonate	15.00	15.00
Tetrasodium Pyrophosphate	5.00	5.00
Ethylene Maleic Anhydride (Copolymer EMA Resin DX 50-81)	0.4	
Dyes, Perfume and preservative	.625	.525
Sodium Sulfate	79.475	79.075
	100.00	100.00

The only difference between the two Formulas C and D is the slight decrease in the sodium sulfate level and the addition of the ethylene maleic anhydride copolymer to Formula D. The dried product of these formulas was packaged in what is essentially a constant volume packaging machine. The average percent overweight per package would then be a measure of bead breakdown, as both formulas were run at the same bulk density out of the spray drier. The overweight figure for two production periods are given below:

	Period I		Period II	
	Production (cases)	Percent Overfill	Production (cases)	Percent Overfill
2 ounces	14,100	14.16	9,900	3.02
6 ounces	17,500	6.53	9,000	1.54
11 ounces	10,600	5.92	6,800	1.82

Formula C was packaged during period I. Formula D was packaged during period II. It is evident that the ethylene maleic anhydride copolymer strengthened the bead considerably in Formula D.

EXAMPLE III

Formula B of Example I may be uniformly admixed with potassium dichlorocyanurate to give the latter 6% weight concentration in the mixture which is useable as household dry bleach.

It may be observed that the invention is distinctively characterized by the low amounts of polymer needed to achieve the desired bead strength and attrition resistance. Whereas to varying degrees, other additives such as sugar, certain gums and surface active agents may contribute

toward bead strength, these are required in such large percentages as to either unbalance the desired performance of the product or be uneconomical.

We claim:

- 5 1. A spray drier substantially water soluble product in hollow bead form consisting essentially of a uniform mixture of at least 75% by weight of water soluble inorganic builder salt of the group consisting of alkali metal phosphates, alkali metal sulfates, alkali metal silicates and alkali metal carbonates, and between about 0.1% and 5% of normally solid ethylene maleic anhydride resin which is film forming from solutions and dispersions containing said salt, said resin having the formula:

15 wherein A is hydrogen, n is an integer representing a molecular weight over 10,000 and B is the same as the unit within the brackets except that it has an ethylene linkage in place of two of the hydrogen atoms, said product being characterized by substantially increased attrition resistance resulting from the presence of said resin.

20 2. A product according to claim 1, in which the product contains about 1 to 20% of a water soluble cationic, anionic or nonionic detergent.

25 3. A product according to claim 1, in which the content of said resin is about 0.4% of the product.

30 4. A dry bleach composition comprising the product of claim 1, containing uniformly admixed therein a solid organic chlorinated water soluble bleach material constituting between about 2 to 25% of the total composition.

35 5. The composition of claim 4, in which the spray dried product contains an organic anionic surfactant in an amount sufficient to give the product detergents properties in aqueous solution.

40 6. The composition of claim 4, in which said chlorinated material is of the group consisting of trichlorocyanuric acid, dichlorocyanuric acid and alkali metal salts of dichlorocyanuric acid.

45 7. The composition of claim 5, in which said chlorinated material is of the group consisting of trichlorocyanuric acid, dichlorocyanuric acid and alkali metal salts of dichlorocyanuric acid.

50 8. The composition of claim 4, in which said product contains between about 1% and 5% of an organic anionic surfactant and said chlorinated material is an alkali metal salt of dichlorocyanuric acid.

9. A spray dried product according to claim 1 wherein said water-soluble solids comprise a surfactant selected from the group consisting of sulfated and sulfonated anionic synthetic detergents, cationic long chain alkyl quaternary ammonium compounds and fatty acid amides and nonionic polyoxyethylene ethers.

55 10. A dry bleach composition according to claim 9 including 1-5% of said surfactant, the balance of said composition being essentially alkali metal salt of chlorinated cyanuric acid.
